UNITED STATES PATENT OFFICE.

RALPH H. UPSON, OF BROOKLYN, NEW YORK.

DIRIGIBLE.

Application filed March 29, 1922. Serial No. 547,598.

This invention relates to airships which have been commonly termed dirigibles, and involves lighter-than-air craft with means of propulsion. More particularly it relates in general, to the rigid and semi-rigid lighter-than-air craft, and among the objects are the production of such craft which will be safer with respect to fire, more durable under the variations of weather conditions, and to produce a ship of maximum strength and stability with minimum of weight and resistance.

Further objects, some of which may be used independently, involve features of internal construction assuring facility of production, assembly and operation, providing for the accommodation throughout the structure of proper electrical conditions, proper and adequate gas-holding properties, and various other features and advantages as will hereinafter appear. With respect to electrical qualities, certain embodiments of my invention give absolute assurance of complete electrical continuity for equalization of electric potential with the advantages incident thereto.

While many or all of these features may be embodied in a single structure, I have illustrated in the accompanying drawings forming a part hereof, a particular embodiment specifically described with respect to the figures, in which:

Fig. 1 is a side elevation, with fragmentary vertical section.

Fig. 2 is a vertical cross-section on line 2—2 of Fig. 1.

Fig. 3 is a vertical cross-section on the line 2—2 of Fig. 1, showing certain modifications.

Fig. 4 is a fragmentary section on enlarged scale showing a typical construction of envelope at the top.

Fig. 5 is a fragmentary transverse section on a still larger scale, of one of the girders shown in Fig. 4.

Fig. 6 is a fragmentary cross-sectional view in alternate form, of one seam shown in Fig. 5.

Fig. 7 is a fragmentary cross-sectional view in alternate form, of a seam of the envelope encased.

Fig. 8 is a fragmentary cross-sectional view in modified form.

Fig. 9 is a fragmentary view showing gas-tight joint of diaphragm on cable.

Fig. 10 is a fragmentary view showing

telescoping diaphragm connection of gas-tight joint on cable.

The particular embodiment of my invention herein illustrated consists of an elongated cigar-shape envelope, with the particular internal tackle or cable arrangement with special arrangement of ballonet diaphragm, but with the longitudinal girders at the outside of the hull connected one to the other by sheet metal. In general, the inventions hereinafter described apply in particular to what may be generally termed an all-metal dirigible, particular reference being to the metal envelope.

The envelope 1 is built-up with the keel or corridor girder 2 and a plurality of longitudinal girders 3 substantially from end-to-end of the ship with sheet metal panels 4 intermediate the longitudinal girders. The panels 4 are secured to the girders by means of a seam 5 forming a gas-tight joint.

In this manner the panels, interconnected by the longitudinal girders, form the envelope for the gas-content throughout the upper portion of the ship, and the ballonet is formed longitudinally throughout the lower portion of the ship by the diaphragm 6 cooperating with the airtight metal envelope forming the lower portion of the ship. In order that the ballonet may expand or deflate to provide increased internal pressure and the variations in the volume of the contained gas in the upper and the major portion of the envelope, suitable air vents or valves are provided and the diaphragm 6 is secured by a seam 7 longitudinally of the ship and in the middle longitudinal section of the ship the cables 8 pass through the diaphragm and are attached to the keel girder 2, and the diaphragm carries sliding gas-tight sleeves 9 which permit the diaphragm to move up and down without hindrance from the cables 8. As shown in Fig. 2 the diaphragm is secured at seam 10 to the partition 11, which is one of several transverse partitions which may be embodied to divide the gas space into a plurality of sections. As shown in Fig. 1, such partition is laterally bulging at 11^a, being formed so as to permit a limited deflection to accommodate the variation in pressure of adjacent gas sections.

The internal cables 12—12 run from the inner edge of the girders 3 to the centre, and are connected to the axial or centre cable 13 of the ship. The outer end of the cables

12 may be sub-divided into crowfoots leading with a plurality of sub-cables to different points in each longitudinal girder to distribute the strain. Strain cables 14-14 may be run from longitudinal girders below the horizontal centre and tied up with cables 15-15 to distribute strains.

As shown in Fig. 3, a radial cable from girder 3^a may be omitted at various transverse sections of the internal tackle, and be supplanted by a vertical cable 16 running to one of the upper longitudinal girders, such as 3^b, thus providing a substantially vertical portion of this cable at the point where it passes through the ballonet diaphragm. At the point of passage of such a cable 16, a similar gas-tight sleeve, such as provided at 9, serves a like purpose. This gas-tight sleeve may be as shown in Fig. 9, or a telescoping sleeve as shown in Fig. 10.

The outer envelope involves the longitudinal girders 3 which preferably have an extended girder plate 16^a with projecting lips 16^b on either side. These lips, as shown in Fig. 5, are bent to form a hook-edge into which the hook-edge 4^a of the envelope metal sheets engages, and with suitable packing or caulking the joint or seam is then secured by rivets to form the gas-tight connection between girder edges and metal panel plates. The other side members 17-17 of each girder converge inwardly and support a suitable anchor attachment 18 for the radial cables or crowfoots and sub-cables.

35 As shown in Fig. 6, the girder plate edge has a tough fabric or leather strip 19 secured to it, with the other edge of this strip 19 attached to the edge of the metal panel plate at joint 20, thus providing between the metal panel strip and the girder a more flexible connection, which may be fire-proofed in any suitable manner.

40 As shown in Fig. 7, the joint involves a hinge with pin 21 connecting the edges of the girder plate and the envelope panel, and the hinge is then covered on the inside with gas-tight tape securely cemented to make the joint gas-tight, and a similar covering 23 on the outside assures gas-tightness and 45 weather protection for the joint. In Fig. 8 a plain lap riveted joint is similarly covered inside and outside by gas-tight tape.

In the completed structure motor gondolas 24 are supported by braces 25 to suitably 55 distribute the strain due to the propeller 26. The keel or corridor girder 2 has suitable gangways leading to crew or passenger engine gondolas 27-27. Fins 28 provide for horizontal rudders 29 and vertical rudders 30.

While I have shown in the fragmentary section Fig. 1, two vertical partitions, in certain embodiments of my invention the horizontal ballonet diaphragm 6 may be continued substantially from end-to-end

without interruption. In the particular form of dirigible herein described, the structure more particularly contemplates longitudinal girders with continuous interconnecting panel plates or sheets forming the sole spacing members circumferentially between the girders. The sheet metal panels

are of extremely thin gauge, and in order to provide the necessary lightness are made of metal of extremely high tensile strength, to serve the purpose of resisting circumferential strain due to internal gas pressure, and as they comprise a continuous envelope they admirably accommodate and resist the sheering stresses. On account of their very

light gauge they are flexible and therefore will bulge between their attaching seams to the girders, thus permitting a limited amount of play to accommodate the internal gas pressure, but it will be understood that beyond certain limits of leeway

internal ties or ribs may be provided to prevent any bulging or deformation beyond the safe limit. It will be noted in Fig. 1 that the stiff longitudinal ribs or girders

have a continuous longitudinal curvature, converging at each end; and that the hull length is less than four times the maximum diameter, so that the curvature of the girders is appreciable at all parts of their length. These with the internal suspenders and the tension and sheer stress wires and cables, as shown, connecting some of the longitudinal ribs, and interconnecting to carry load

strains to the corridor girder, all combine to form a truss structure of ribs longitudinally. This, with the metal sheathing between the ribs, it will be seen from the drawings, provides for circumferential stresses, and all together provide for a complete stiff hull. This in effect provides a rigid airship hull in which the stresses due to static loads when inflated are carried in the skin of the ship itself and directly transmitted to the internal tie wires and suspender cables, and in which the longitudinally stiff girders are, as shown, embodied directly as a permanent part of the skin of the ship. While the ballonet inflation

serves to provide additional internal pressure to compensate for increased aerodynamic pressure from without.

The internal tackle it will be seen, is so arranged as to distribute the suspension loads, and for longitudinal oblique strains additional cross cables, such as 31-31, may be provided, which, as shown, carry the strains from cable crossing points through the ballonet diaphragm at a point where the same requires no movement such as at the seam where the diaphragm is attached to a partition wall as there shown. When dimensions of the ship permit, no diagonal cables need be used, the construction of metal envelope and girders being such as to pro-

90

vide for the accommodation of sheer stresses.

It will be understood that the buoyancy strains and the strains due to aero-dynamic forces in flight, will be accommodated by the structure as heretofore described, but the strength of panels suitable therefor, would not in many cases provide the necessary support for the girder weight in the absence of internal gas pressure, and in order to facilitate assembly and to maintain a structural unity when assembling or in the absence of internal gas pressure, suitable interconnecting braces between girders may be provided, which while suitably supporting the structure under abnormal conditions will not interfere with the proper functioning to the great advantage of the combination of metal panel plates and other features of construction heretofore described.

20 I claim—

1. In a dirigible, a complete metal gas enclosing envelope, a plurality of rigid meridian girders having appreciable curvature throughout their length, forming part of the metal envelope and having intermediate said girders thin metal plating, a substantially horizontal flexible diaphragm attached to said envelope along each side below the middle, a plurality of load cables 25 passing through said diaphragm and interconnecting a bottom girder with the meridian girders on the upper half of the hull.

2. An airship comprising a plurality of girders extending from end-to-end along 30 meridians of the hull with a convex curvature throughout each girder, thin sheet metal flexible plates extending circumferentially intermediate all of said girders throughout the upper half of the ship and substantially 35 below the middle forming with said girders a contiguous longitudinally stiffened gas-tight envelope and hull skin combined, flexible horizontal balloonet diaphragm in the lower hull section extending between meridian girders on each side, interior load lacing, and interior suspension cables extending 40 from the lower hull through the balloonet diaphragm and diverging to a plurality of upper longitudinal girders.

50 3. In a dirigible, a complete airtight metal envelope comprising a plurality of continuous longitudinal stiff girders from end-to-end of the hull having convex curvature in all parts of their length and being gas-tight 55 jointed and inter-connected with thin metallic plating and a transverse flexible diaphragm forming a partition of a variable segmental portion as a minor portion thereof at the bottom.

60 4. A dirigible comprising a single envelope of metal on the outside forming the skin of the hull and incorporating therein a plurality of rigid meridian girder structures from end-to-end disposed from below the 65 middle on one side and spaced throughout

the upper hull to below the middle on the opposite side, a fabric diaphragm on the inside thereof forming a flexible balloonet roof in the bottom portion of the hull.

5. A dirigible comprising plural meridian 70 metal girders from end-to-end spaced by direct connected thin metallic sheathing to form a contiguous single metallic gas envelope and hull skin combined, an accentuated girder structure extending from end-to-end 75 combined with the metallic sheathing and positioned in the lower half of the hull, internal lacing inter-connecting the girders whereby the single metallic envelope serves to carry tangential and sheer stresses due 80 to static loads and aerodynamic pressure.

6. A dirigible comprising a metal envelope, a plurality of members providing longitudinal rigidity forming longitudinal girders incorporated in or forming a part of the metallic envelope extending from end-to-end and spaced circumferentially throughout the upper half and part way down the sides, and envelope connections between said members to provide circumferential yielding 85 to a natural curvature dependent upon the relation between internal and external pressure.

7. A rigid airship comprising an outside 90 metal sheathing hull skin constituting also the sole gas-retaining envelope throughout the upper half and part way down the sides below the horizontal meridians, a plurality of stiff longitudinal meridian members convex throughout their length with the intervening metal sheathing forming a shear-resisting non-deformable hull, a flexible generally horizontal diaphragm extending from side-to-side of the non-deformable hull at or 95 below the middle and an airtight space below said diaphragm whereby air pressure may be provided underneath the diaphragm to increase the gas pressure on the inside of the non-deformable envelope, and excess gas pressure is accommodated by a yielding of 100 the diaphragm to permit the desired pressure on the inside of the envelope with respect to the aerodynamic or aerostatic pressure on the outside surface of the metal envelope without resisting all of said excess 105 strains solely by the hull structure.

8. In a rigid airship, a thin metallic envelope susceptible to flexing between stiff girder members incorporated with the envelope, a plurality of stiff longitudinal girder 110 members united to the inner surface of the envelope on a series of meridian lines throughout the hull, a flexible substantially horizontal diaphragm extending longitudinally at or below the middle of the ship and 115 united on both sides to the inside of the metal envelope forming a buoyant gas envelope between the diaphragm and the non-deformable upper hull section and an airtight space below the diaphragm, whereby 120 125 130

lift section of the hull is relieved of excess aerostatic strains by the yielding of the diaphragm and whereby excess aerodynamic strains on the non-deformable hull may be resisted by increased air pressure below the diaphragm.

9. A rigid airship comprising metal sheathing constituting in one the hull skin and buoyant gas-confining envelope, a plurality of stiff longitudinal members having curvature throughout their length combined with the surface of the metal sheathing on substantially meridian lines providing a substantially non-deformable hull permitting only slight flexing of the metal sheathing between the stiff members while carrying the shear and tangential stresses of the hull by the envelope, gas-tight joints associated with the union of the flexible plating with the stiffening members, and a flexible diaphragm having gas-tight connections on each side of the hull longitudinally of the ship, separating a sub-air space from the superposed gas space whereby variations of pressure will prevent excess strains in the non-deformable hull structure by suitable yielding of the diaphragm.

10. A dirigible comprising a complete metallic envelope on the outside, a substantially horizontal diaphragm below the middle and attached on a longitudinal line along the inside of the metal envelope, substantially radial metal cables extending from the metal envelope above the diaphragm to a common point about the approximate longitudinal axis of the dirigible, substantially vertical cables extending upward from the bottom portion of the metal envelope through the diaphragm and a gas-tight joint at the point of penetration of each cable with the diaphragm.

11. A rigid airship comprising a substantially complete metal sheathing hull constituting the sole buoyant gas-retaining envelope and hull skin combined, consisting principally of thin metal panels with a plurality of rigid longitudinal members spaced on meridian lines generally equi-distant over the upper portion of the hull and down both sides below the middle with convex curvature throughout their length, air-tight seams between said light metal panels and at junctions of the panels with rigid longitudinal members, a flexible generally horizontal diaphragm longitudinal of the ship adapted to yield to the varying gas pressure above, an air space below the diaphragm whereby upward pressure thereon may be controlled, and an exaggerated girder united with the lower hull portion at or below the gas-tight lateral seams of the flexible diaphragm.

12. A rigid airship comprising a rigid girder in the bottom portion, a plurality of longitudinal rigid girders substantially uniformly separated extending on meridian lines along

the sides and throughout the top portion of the hull having convex curvature longitudinally throughout, intervening thin sheet metal panels forming with the stiff girders a complete contiguous hull skin and lift gas-confining envelope, a generally horizontal flexible diaphragm united with the inside of the skin at or below the middle, a plurality of vertical flexible gas partitions extending from said horizontal diaphragm to the skin of the ship above, whereby surging of the buoyant gas is prevented by the partitions, and excess gas pressures are accommodated by the substantially horizontal diaphragm.

13. A dirigible comprising a substantially complete metal envelope serving as gas retainer and outside skin and having its buoyant gas contact area formed of flexible thin metal sheathing, a series of stiff girder members united with the sheathing providing therewith a shear stress-resisting hull skin, lap-joints connecting the edges of adjacent panels of the sheathing and panels with stiff girder members adapted to carry the hull stresses and gas-tight tape covering the seam and hermetically connected and secured to the adjacent panel surfaces.

14. In an airship a gas confining non-deformable envelope and ship-skin in one, formed of thin metallic sheathing, hull strain-resisting seams rigidly interconnecting the adjacent edges of the metallic panels or plates and gas-tight tape cemented over said seams.

15. In an airship, a longitudinal triangular girder having a relatively wide cord plate substantially in the plane of the dirigible envelope, projecting lateral edges on said girder and means on said projection for attachment of adjacent metal panel plates.

16. In an airship, a nondeformable outside hull skin and gas-containing envelope, a plurality of longitudinal girders extending from end-to-end of the hull having one chord face lying substantially in the plane of the inner surface of the skin of the hull projecting inwardly therefrom into the buoyant gas space and incorporated therewith, metal sheathing interconnecting said girders and jointly therewith forming said sole gas-tight envelope and hull skin combined.

17. In an airship, a plurality of triangular meridian girders extending from end-to-end of the ship and spaced circumferentially, one chord of each triangular girder being incorporated with a metallic hull shell to form a contiguous metal sheathing and gas envelope substantially as described.

18. In an airship, a metallic hull skin and gas envelope combined, comprising a primary large corridor truss in the lower half of the hull, a plurality of triangular section longitudinal girders extending end-to-end and spaced circumfer-

throughout the top and sides of the hull, thin metallic sheathing incorporated with the outer chords of said triangular girders and forming therewith the gas-tight envelope and interconnecting sheer resisting lacing.

19. In a dirigible, a substantially complete metal envelope, a plurality of thin sheet metal panels forming the main part of 10 said envelope, a plurality of rigid continuously curved longitudinal ribs extending from end-to-end and frequently spaced throughout the upper half and part way down the sides of the hull and seams between 15 the adjacent metal members of the envelope forming gas-tight means for permanently securing the members of the metal envelope as a permanent sheer stress resisting structure.

20. In a dirigible, a complete metallic envelope, interior lacing interconnecting stiff envelope ribs, a balloonet along the bottom of said envelope, a flexible diaphragm forming the ceiling of said balloonet and gas-tight 25 sliding joints at the points that the interior lacing penetrates said diaphragm.

21. In a dirigible, a plurality of stiff longitudinal members reaching substantially from end-to-end and of a number providing a series circumferentially spaced throughout 30 the upper half and part way down the sides of the hull, rigidly interconnected by thin sheet metal plates forming a continuous gas envelope and hull skin, a substantially axial tie member extending from end-to-end of 35 the ship.

22. In an airship, a plurality of stiff longitudinal members circumferentially spaced coincident with the shell of the hull and having appreciable curvature throughout 40 their length, an axial tie member extending from end-to-end of said longitudinal girders and thin metallic sheathing permanently incorporated with said longitudinal members and forming therewith a continuous metallic hull sheathing and gas envelope in one.

In testimony whereof, I have signed my name to this application this 28th day of March, 1922.

RALPH H. UPSON.
